AIR CONDITIONING SYSTEM

William R. Shepperd, St. Louis, Mo., assignor to
Lewis L. Scott, St. Louis, Mo.

Application March 16, 1935, Serial No. 11,396

10 Claims. (Cl. 62—178)

This invention relates to an air conditioning system particularly adapted to heat or cool houses, and has for its object an improved system which is exceedingly simple and reliable in operation, as well as economical and inexpensive.

The majority of air conditioning systems for complete heating and cooling utilize, as the means of producing cold, compressors and electric motors which are high in first cost, noisy, and high in operating cost. In addition to this type of equipment they utilize some means of heating for the winter season consisting of an oil or gas burner, together with a heat absorbing medium, so that the complete plant for winter and summer air conditioning gets very expensive. My system contemplates the use of any source of heat, such as oil or gas, to accomplish both the heating and cooling job, and in connection with cooling I use an ejector to create a vacuum in the cooling coil. In my system I have discovered a refrigerant that lends itself to this type of system that has never been used (to my knowledge) before. My system is hermetically sealed and free from moving parts, thereby being quiet in operation and very durable.

The apparatus shown in my drawings for carrying out my invention consists of an evaporator, containing a body of liquid refrigerant in thermal connection with the body of air or other substance to be cooled; a boiler in which, by means of a source of heat, another body of the same refrigerant liquid is raised to a high temperature, the vapor pressure being correspondingly raised; an ejector wherein the high pressure vapor from the hot liquid is accelerated to a high velocity by expanding it through a nozzle, the high velocity stream of vapor being so disposed as to entrain vapor from the first mentioned body of refrigerant, the mixed stream of vapor then being expelled through an outlet by its own velocity; and a condenser, wherein the heat of vaporization is removed from the vapor that issues from the ejector; together with such accessories as are required to remove the condensed refrigerant from the condenser and replenish the supply in the evaporator and the boiler as required. It is understood that other accessories will circulate the air or other matter being cooled by the evaporator and that a sufficient supply of air, water, or other coolant will be provided for removing the heat from the condenser. I also provide in my system an arrangement whereby, by use of a check valve and a shut-off valve, I can adapt and utilize this same apparatus, in-

cluding the refrigerant, for complete heating and winter air conditioning.

I am fully aware that ejectors have been used in connection with refrigeration cooling systems where water is used as the refrigerant. Such a system requires the use of three ejectors in order to produce a vacuum on the water to be cooled at approximately 29 $\frac{3}{4}$ " because of the exceedingly low vapor tension of water, and in order to get economy steam pressures must be used at approximately one hundred pounds or more. State laws do not permit the use of high pressure steam without a licensed engineer attendant, which would not be practical for household use. A pump of considerable size is required to circulate the cool water and another pump removes the condensate and returns it to the boiler. I am also aware of the fact that a cooling system using an ejector with some refrigerant other than water has been proposed, but never to my knowledge been put into successful operation, due largely to the fact that no suitable refrigerant has been found that would give economical results in a system of this type.

Among the refrigerants that have been suggested, chloroform, the various alcohols, and the ethers except ethyl ether, boil under such excessively low pressures, or high vacua, that they can be used successfully only in a cooling device adapted to expose a thin layer of the liquid refrigerant; if used in a tubular refrigerating coil of conventional design, adapted to boil the refrigerant within the tubes, only the uppermost layer of the refrigerant will be cooled to the desired temperature, and the portion in the lower part of the cooling coil will be progressively warmer, with consequent decreased cooling effect. Another fault of this class of compounds is their inflammability; all of the alcohols and ethers including ethyl ether, are inflammable, and are explosive when their vapors are mixed with air. This fire hazard makes them unsuitable for use in unattended domestic installations. Many substances of these classes are dangerous poisons, being anaesthetics that will render a person unconscious, as well as produce death; they are therefore not safe for use in cooling coils which are used directly for cooling air that is to be breathed.

Carbon disulfide is both violently poisonous and inflammable, hence is unsuitable for this use.

Carbon tetrachloride is not inflammable, in fact it is an efficient fire extinguisher; but it is sufficiently toxic to constitute a hazard when present in the quantity required for air cooling.

service, hence it is unsuitable for domestic use. It boils under too low a pressure to be efficient in a conventional cooling coil.

All of the petroleum derivatives are very inflammable, and most of them are toxic as well, making them unsuitable for domestic service.

The refrigerants commonly used in compression machines, such as ammonia, sulphur dioxide, dichlorotetrafluoroethane, dichlorodifluoromethane, methyl chloride, etc., if used in an ejector system would require boiler pressures of several hundreds of pounds; in most of them the boiler would operate above the critical temperature of the refrigerant. It is difficult to construct a boiler to withstand the pressures, and even more difficult to replenish the liquid refrigerant in the said boiler as it is vaporized.

Methylene chloride, commercially known as carrene, can be used in an ejector system, and has satisfactory pressure characteristics; it is almost non-inflammable, and is reasonably non-toxic. In service, however, its efficiency is impaired by the condensation of a considerable portion of the vapor into liquid during its expansion in the nozzle of the ejector; the portion condensed is in the form of droplets which pass through the low pressure vapor without imparting to it all of this velocity. The said droplets have also a tendency to erode and roughen the surfaces of the ejector nozzle and throat along which they are driven, causing a progressive lowering of efficiency as the surfaces become roughened and impose increasing friction upon the vapor during its expansion. Such friction lowers the efficiency of the ejector by reducing the velocity of the jet of vapor, issuing from the nozzle, and also by increasing the turbulence of the vapor in that jet, which makes the high velocity jet of vapor less effective in entraining the low pressure vapor that is drawn from the cooling coil.

The distinguishing features of the refrigerants, the use of which in the ejector system constitutes this invention are:

45 When any one of my refrigerants in the form of saturated high pressure vapor is supplied to the ejector nozzle there is either no condensation or a negligibly small amount of condensation during expansion. Such condensation would be a source of waste in a number of ways as above enumerated. My refrigerants used in the present invention condense little if at all when expanding in a nozzle. Thermodynamically the expansion characteristic is expressed by saying 50 that the entropy of saturated vapor shall increase slowly or not at all with decreasing temperature. I have found that for best results the maximum condensation permissible is six percent; this is determined for any specific substance as follows: 55

60 Let (a) represent the entropy of saturated vapor at the temperature at which it comes from the boiler.

Let (b) represent the entropy of saturated vapor at the pressure prevailing in the evaporator.

65 Let (c) represent the entropy of liquid refrigerant at the temperature and pressure prevailing in the evaporator.

Then (a) must not be less than $.94b + .06c$.

In order to keep the evaporator or cooling unit 70 down to a practical size and to eliminate such accessories as circulating pumps, film type evaporators, spray type evaporators, etc., the pressure in the evaporator must not be less than three pounds per square inch, absolute (not 75 gauge) pressure. At this pressure the boiling

temperature of the refrigerant will not increase more than five degrees per foot depth, so that the temperature throughout the evaporator will be substantially uniform; and the volume of vapor liberated will be small enough to require a 5 moderate size of conduit.

In order that safe apparatus may be built at moderate cost the refrigerant must be such that the pressure in the boiler will not exceed 300 pounds per square inch under the highest possible operating temperature. This temperature will vary with the nature of the application; typical cases will be the use of low-pressure steam as a source of heat, with a maximum possible temperature approximately 240° F. and average 10 operating temperature a bit over 200° F.; or the use of a direct fired unit, with temperature and pressure limited by thermostatic or pressure actuated means or both, wherein the working temperature may with a suitable refrigerant go to 15 300° F. without exceeding 300 pounds pressure. 20

The refrigerant must be chemically inert and stable under operating conditions. By inert is meant that at the temperature encountered, and in the presence of traces of air that are likely 25 to occur in the refrigerating apparatus, they shall not attack iron, copper, brass, and other commonly used structural metals or be decomposed by contact with them.

The refrigerants in order to be entirely safe 30 in service must be non-toxic under conditions and concentrations encountered in service, and must be non-inflammable in order that the moderately large plants required for air conditioning in-service shall be free from fire hazard when installed in a building. 35

I have found that at least three refrigerants comply with all of the above mentioned conditions. These refrigerants are:

A compound commonly called F-11 which is 40 commercially known as fluorotrichloromethane (CFC_3).

A compound commonly called F-113 which is commercially known as trifluorotrichloro-ethane ($C_2F_3Cl_3$).

A compound commonly called F-21 which is 45 commercially known as fluorodichloromethane ($CFHCl_2$).

Various other advantages will be apparent 50 from the following detailed description of an embodiment of the invention, and the novel features will be particularly pointed out hereinafter in connection with the appended claims.

The accompanying drawings illustrate diagrammatically a simple system constructed in 55 accordance with my invention.

Figure 1 is a diagrammatic drawing of my complete air conditioning system.

Figure 2 is an enlarged sectional cut of my transfer unit which functions to transfer the 60 liquid from the condenser back to the boiler.

Figure 3 is an end sectional view taken on the line 1—1 of Figure 2.

Figure 4 is an end sectional view taken on the line 2—2 of Figure 2.

I will first describe my system as it operates 65 for cooling purposes.

Referring now to the drawings, the numeral 1 indicates a gas burner which is automatically controlled by the room thermostat 2, and which 70 is ignited by the pilot light 3. The numeral 4 indicates a motor operated valve in the main gas line, the operation of which is controlled by the room thermostat as well as by certain other controls which will be later described. The numeral 75

5 indicates boiler coils for absorbing heat from the burner 1, which coils are connected to the top header of the boiler indicated by the numeral 6. The numeral 7 indicates the chimney through which the products of combustion from the burner pass to the outside atmosphere.

The liquid refrigerant above referred to is contained within the boiler coils 5 and top header 6, and when the burner 1 is in operation, the liquid refrigerant is heated and vaporized and passes under pressure through the pipe 8 to the ejector nozzle 9 and issues from said nozzle at high velocity, and passes through the body of low pressure vapor 10 and imparts some of its motion to this low pressure vapor, and the combined stream is literally thrown through the Venturi opening 11 into the condenser 12 where a higher pressure than that of the cooling coil 13 is maintained. The condenser 12 contains pipes 14 through which cool water passes for condensing the vapor just referred to, the vapor giving up to the water the heat that it has removed from the air in the house.

My refrigerant has high vapor density and moderate pressure; hence, the size of the ejector is moderate and its efficiency high.

A float valve 15 which is contained in an enlarged header connected with the cooling coils 13 handles approximately twelve gallons per hour of the refrigerant for each ton of cooling capacity. The numeral 16 indicates a back pressure limit switch for breaking the circuit to the motorized valve 4 in case of failure of the cool water supply to the condenser coil 14. The numeral 17 indicates a high temperature cut-out switch to protect the boiler in case of running dry—this cut-out switch is also a protection against excess boiler pressures and acts to break the circuit to the motorized valve 4 in case of excessive pressure or temperature. The current is furnished for operating the motorized valve 4 through the power wires 18 and 19. The numeral 20 indicates the conventional hand shutoff switch.

The numeral 21 indicates a metal cabinet 45 which contains an air blower 22 adapted to suck air through filters 23 from the rooms to be cooled and over the cooling coil 13 and deliver it through the duct 24 to pipes not shown connected with the rooms to be cooled.

The evaporator or cooling coil 13 is constantly filled to a certain level with liquid refrigerant; as this liquid evaporates due to absorbing heat from the air passing over it, the float valve 15 admits more liquid refrigerant to replace it. The liquid refrigerant passes from the lower part of the condenser 12 through the pipe 25 and is controlled by the float valve 15 as before described. The pressure produced by the ejector in the condenser 12 serves to force the liquid refrigerant 60 through the float valve 15 back to the evaporator as rapidly as said float valve permits. The remaining liquid from the condenser 12 flows by gravity through valve 26 into the transfer unit 27. In the position shown in the drawings vent pipe 28 communicating with the condenser 12 is open through relief pipe 29 to the body of the transfer unit. The hydrostatic pressure of the refrigerant liquid cooling from the condenser through pipe 30 lifts the valves 26 so that the liquid enters the float chamber to displace gas being vented through pipes 28 and 29. When the liquid level has raised sufficiently, the float 31 moves, operating rod 32 and vent valve 33 up to a position where pipe 28 to the condenser is closed and pipe 34 to the boiler is open. Under

this condition the hydrostatic pressure of the liquid in the float chamber 27 opens valve 35 and liquid flows through outlet pipe 36 into the boiler. As soon as the liquid level is lowered, the float 31 causes rod 32 and valve 33 to move down, closing off pipe 34 and the float chamber is again filled from the condenser as before described. It will be noted that pipe 30 extends slightly above the bottom wall of condenser 12 and that pipe 28 extends still further above the bottom wall of the condenser 12 than does pipe 30. The transfer unit is shown in more detail in Figures 2, 3 and 4 in slightly modified form, as in Figure 1 it is merely shown diagrammatically in the complete system. In the construction shown in Figure 2 of the transfer unit, the float 31 is adapted to slide on the rod 32, which rod is connected to the piston valve 33. The float 31 is adapted to move coil spring 37 which eventually contacts an enlarged portion of valve 38 on the shaft 32. The numeral 39 indicates flat springs which engage in notches in the shaft 32 and are secured in grooves in the head 40 of the transfer unit 27. The numeral 41 indicates a spring similar to 37 located on the lower side of the float 31. This arrangement permits the valve 33 to be moved into and from the positions, above described, by snap action which insures full travel of the valve 33 from fully open, through pipe 28 to fully open through pipe 34, or vice versa. The valve 33 being in the form of a piston valve with ports all around its periphery is perfectly balanced; hence, takes very little power to operate and the snap action device insures it against eroding of the edges of the valve and seat. The above described transfer unit permits automatic transfer of the liquid refrigerant from the condenser to the boiler in a completely hermetically sealed device without the use of any motors or pumps.

When it is desired to use my air conditioning system for winter operation for heating instead of cooling, the valve 42 is opened thereby permitting the vapor from the boiler to pass through the pipe 8 and the pipe 43, and through the valve 42 into the pipe 44, thence to the coils 13. The condensate will return to the boiler through the pipe 45, which pipe has a check valve 46, which valve permits the flow of the liquid to the boiler, but prevents any back flow of liquid from the boiler. Blower 22 functions to move the air from the rooms, which air passes over the coil 13 and is heated and is transferred through the duct to the rooms. When this system is used for heating in winter the thermostat 2 is arranged to turn the burner 1 on when the temperature drops below 70°. The control 16 which limits the pressure in the condenser 12 functions during the winter operation as well as the summer operation to protect the condenser and connected parts against excessive pressure. During the winter operation no water is used in coil 14 in the condenser 12; this condenser will be filled with vapor from the boiler 6 and will thereby be maintained at the same temperature as the cooling coil 13. Condenser 12 will therefore be covered with some sort of insulating material to retain this heat and prevent it from acting as a radiator; the liquid condenser under these conditions will flow back to the boiler in the same manner as before described when the system is operating as a cooling device.

I have given three refrigerants that meet my requirements in such a system as above described; however, I prefer to use F-113, which

is commercially known as trifluorotrichloromethane. I have found that this fluid meets all of the requirements in the cooling as well as the heating cycle. The characteristics of F-113 are 5 as follows:

Boiling point under atmospheric pressure 118° F.

The vapor pressure of this fluid in the cooling coil 13 when operating as a cooling plant is 3.6 10 pounds per square inch absolute at 50° F. Under the same conditions of operation, the pressure in the condenser 12 is about twelve pounds per square inch absolute at 110° F. (Wherever cooling coil is used in this description it is understood 15 that the meaning intended is a device wherein heat is transferred from the refrigerant boiling under low pressure to the air or other medium that is being cooled.)

The pressure in the boiler 8 is approximately 20 135 pounds per square inch absolute at 300° F. which is the preferred operating temperature of the fluid in the refrigeration cycle.

The specific volume of the vapor issuing from 25 the cooling coil 13 is eight cubic feet per pound and its latent heat is sixty-six B. t. u. per pound.

When the unit is operating for heating instead of cooling the vapor pressure in the cooling coil 13 is approximately twenty-eight pounds per square inch absolute. Under this condition the 30 vapor density is 1.1 pound per cubic foot and the latent heat is approximately fifty-nine B. t. u. per pound.

The molecular weight of this substance is 187.4. The specific heat of the liquid at 70° F. is 0.198. 35 The density of this liquid at 70° is about ninety-eight pounds per cubic foot.

I claim:

1. In an ejector system of refrigeration, a device for transferring the liquefied motive fluid 40 from the condenser to the boiler, said device consisting of a vessel located above the boiler, said vessel having a liquid inlet pipe from the bottom of the condenser into the vessel provided with a non-return valve, and also liquid outlet 45 pipe leading from the bottom of the said vessel into the boiler, this outlet also being provided with a non-return valve, said vessel also having a device whereby a vent at the top of the vessel is connected alternately, first to the condenser, 50 causing refrigerant liquid to flow from the condenser through the first mentioned non-return valve into the said vessel; the said vent then being connected to the boiler, into which the refrigerant liquid flows through the second mentioned non-return valve by gravity.

2. The process of refrigeration comprising extracting heat from space surrounding a liquid refrigerant by evaporation intensified by entraining vapors from said liquid in a stream of expanding refrigerant gas to reduce the pressure on 55 said liquid, said refrigerant comprising one of the group of halo-fluoro derivatives of an aliphatic hydrocarbon, including fluoro-dichloro-methane, fluoro-trichloro-methane and trichloro-trifluoro-60 ethane.

3. The process of refrigeration comprising extracting heat from space surrounding a liquid refrigerant by evaporation intensified by entraining vapors from said liquid in a stream of expanding refrigerant gas to reduce the pressure on 65 said liquid, said refrigerant comprising a halo-fluoro derivative of an aliphatic hydrocarbon, which will boil at evaporator temperature at a pressure not less than three pounds per square inch absolute, and which has a pressure 70 of not more than three hundred pounds per square inch for saturated vapor at a temperature of 300° F., and which when expanded in an ejector with a theoretically perfect frictionless nozzle from boiler pressure to evaporator pressure will have not to exceed six per cent condensation.

more than three hundred pounds per square inch for saturated vapor at a temperature of 300° F.

4. The process of refrigeration comprising extracting heat from space surrounding a liquid refrigerant by evaporation intensified by entraining vapors from said liquid in a stream of expanding refrigerant gas to reduce the pressure on 5 said liquid, said refrigerant comprising fluoro-dichloro-methane, CHFCl_3 .

5. The process of refrigeration comprising extracting heat from space surrounding a liquid refrigerant by evaporation intensified by entraining vapors from said liquid in a stream of expanding refrigerant gas to reduce the pressure 10 on said liquid, said refrigerant comprising fluoro-trichloro-methane, CFC_3 .

6. The process of refrigeration comprising extracting heat from space surrounding a liquid refrigerant by evaporation intensified by entraining vapors from said liquid in a stream of expanding refrigerant gas to reduce the pressure 15 on said liquid, said refrigerant comprising tri-chloro-trifluoro-ethane, $\text{C}_2\text{Cl}_3\text{F}_5$.

7. The process of refrigeration comprising applying heat to a liquid refrigerant to produce a 20 gas under pressure, extracting heat from space surrounding a body of liquid refrigerant through evaporation of said liquid by entraining vapors from the surface of said body in an expanding stream of said gas under pressure to reduce the 25 pressure over said body, said refrigerant comprising a halo-fluoro derivative of an aliphatic hydrocarbon having an entropy of vapor at boiler temperature of not less than .94 entropy of the vapor at evaporator pressure plus .06 of the entropy of the liquid at evaporator temperature.

8. The process of refrigeration comprising applying heat to a liquid refrigerant to produce a 30 gas under pressure, extracting heat from space surrounding a body of liquid refrigerant through evaporation of said liquid by entraining vapors from the surface of said body in an expanding stream of said gas under pressure to reduce the 35 pressure over said body, said refrigerant comprising a halo-fluoro derivative of an aliphatic hydrocarbon, which will boil at evaporator temperature at a pressure not less than three pounds per square inch absolute, which has a pressure of not more than three hundred pounds per square inch for saturated vapor at a temperature 40 of 300° F., and which when expanded in an ejector with a theoretically perfect frictionless nozzle from boiler pressure to evaporator pressure will have not to exceed six per cent condensation.

9. The process of refrigeration comprising applying heat to a liquid refrigerant to produce a 45 gas under pressure, extracting heat from space surrounding a body of liquid refrigerant through evaporation of said liquid by entraining vapors from the surface of said body in an expanding stream of said gas under pressure to reduce the 50 pressure over said body, said refrigerant comprising a fluid which will boil at evaporator temperature at a pressure of not less than three pounds per square inch absolute, which has a pressure 55 of not more than three hundred pounds per square inch for saturated vapor at a temperature of 300° F., and which when expanded in an ejector with a theoretically perfect frictionless nozzle from boiler pressure to evaporator pressure 60 will have not to exceed six per cent condensation.

10. The process of refrigeration comprising applying heat to a liquid refrigerant to produce a 65 gas under pressure, extracting heat from space 70

surrounding a body of liquid refrigerant through evaporation of said liquid by entraining vapors from the surface of said body in an expanding stream of said gas under pressure to reduce the pressure over said body, said refrigerant comprising a fluid which will boil at evaporator temperature at a pressure of not less than three pounds per square inch absolute, which has a

pressure of not more than three hundred pounds per square inch for saturated vapors at a temperature of 300° F., and which has a vapor entropy at the boiler temperature of not less than .94 of the vapor entropy at the evaporator temperature plus .06 of the liquid entropy at the evaporator temperature.

WILLIAM B. SHEPPARD.
